UNITED STATES PATENT OFFICE.

ARTHUR C. HOPKINS, OF NILES, MICHIGAN, ASSIGNOR TO NATIONAL-STANDARD COMPANY, OF NILES, MICHIGAN.

LIFTING JACK.

Application filed May 18, 1927. Serial No. 192,269.

The main objects of this invention are:

First, to provide an improved lifting jack which is strong and rigid in structure and at the same time may be formed mainly of 5 stampings.

Second, to provide an improved lifting jack which may be compactly collapsed and is of considerable height when extended.

Third, to provide an improved lifting jack 10 which is easily operated.

Objects pertaining to details and economies of my invention will appear from the description to follow. The invention is pointed out in the claims.

15 A structure embodying the features of my invention is clearly illustrated in the accompanying drawing forming a part of this application, in which:

Fig. 1 is a detail view mainly in vertical 20 section on a line corresponding to line 1—1 of Figs. 2 and 3.

Fig. 2 is a detail view mainly in horizontal section on line 2—2 of Figs. 1 and 4.

Fig. 3 is a fragmentary horizontal section 25 on line 3—3 of Fig. 1.

Fig. 4 is a side elevation of the jack in extended position, parts being broken away to show structural details.

In the embodiment of my improvements 30 illustrated the standard and lifting member parts are formed mainly as metal stampings. The standard designated generally by the numeral 1 is made up of a pair of sections 2, 2 conformed to provide when assembled a

45 gear housing bottom portion 3 and an upright portion 4 of horizontal cross section. These sections have lapping flanges 5 at their edges secured together in the structure illustrated by spot welding as indicated at 6. The base

50 7 which is preferably a casting is secured to the horizontal flange 8 by rivets 9.

At one side the housing portion is extended to form a bearing 10 for the shaft or journal 11 of the driving gear 12. The journal 11

45 is provided with a socket 13 to receive the crank 14.

The gear 12 meshes with a beveled gear 15 55 on the lower end of the driving screw 16, this structure being rotatably supported by the bearing ball 17 on the base plate. Upward movement is prevented by the engagement of the gear 15 with the gear 12.

I provide an extensible lifting member 60 consisting of the bottom section 18 and the top

section 19, both sections being tubular and 55 of rectangular cross section. The lifting member section 18 is formed as a stamping, that is, it is folded up from sheet metal and is slideable within the rectangular portion of the standard.

At its upper end the section 18 has laterally projecting ears 20 and is connected by the cross members 21 which reinforce or 60 strengthen the walls of the member 18 and also form a guide for the member 19. The member 19 has telescoping engagement with the screw 16 and is provided with laterally projecting ears 22 at its lower end which 65 slidably engage the walls of the member 18 to guide and support the member 19 for telescoping movement.

The bottom section 18 is provided with a bottom piece 23 having threaded engagement with the screw 16. This bottom piece or nut member 23 is secured to the lower end of 70 the section 18 and not only drives the same but serves as a support therefor.

Cables 24, which in the structure illustrated are in the form of chains, are secured 75 to the brackets 22 at their inner ends and to the laterally projecting brackets 25 on the standard at their outer ends. Rollers 26 are mounted on the ears 20 of the lifting member section 18 so that as the section 18 is raised by means of the rotation of the screw the section 19 is projected from the section 18. The lifting member section 19 is provided with 80 a head 27.

Jacks embodying my improvements may be 85 compactly collapsed, are economical in structure and may, as stated, be practically formed from stampings.

I have not attempted to illustrate or 90 describe various other modifications and adaptations which I contemplate as I believe the disclosure made will enable those skilled in the art to embody or adapt my improvements 95 as may be desired.

Having thus described my invention what I claim as new and desire to secure by Letters Patent is:

1. In a lifting jack, the combination of a 100 hollow standard provided with a base plate and having a lower gear housing portion and an upper portion of rectangular cross section with laterally projecting brackets at the top thereof, a screw disposed vertically in said standard and provided with a gear 105

at its lower end, said screw being supported by a bearing on said base plate, a driving gear coacting with said gear on said screw, a hollow rectangular bottom lifting member 5 slidable in said upper rectangular portion of said standard to telescope therein and having a driving member secured in its lower end and having threaded engagement with said screw, said lifting member section having laterally projecting ears at its upper end above said brackets on said standard, a tubular rectangular top lifting member section telescoping with said screw and having laterally projecting brackets at its lower end 10 slidably engaging within said bottom lifting member section, said bottom lifting member section having guides at its upper end for said top lifting member section, and cables connected to said brackets on said standard 15 and top lifting member section, said bottom lifting member section having rollers on its said ears over which the cables are passed.

2. In a lifting jack, the combination of a hollow standard provided with a base plate 25 and having laterally projecting brackets at the top thereof, a screw disposed vertically in said standard and provided with a gear at its lower end, said screw being supported by a bearing on said base plate, a driving gear coacting with said gear on said screw, a hollow bottom lifting member telescoping with said standard and having a driving member 30 secured in its lower end and having threaded engagement with said screw, said lifting member section having laterally projecting ears at its upper end above said brackets on said standard, a top lifting member section telescoping with said screw and having laterally projecting brackets at its lower end 35 slidably engaging within said bottom lifting member section, said bottom lifting member section having guides at its upper end for said top lifting member section, and cables connected to said brackets on said standard 40 and top lifting member section, said bottom lifting member section having rollers on its said ears over which the cables are passed.

3. In a lifting jack, the combination of a hollow standard provided with a base plate 50 and having a lower gear housing portion and an upper portion of rectangular cross section, a screw disposed vertically in said standard and provided with a gear at its lower end, said screw being supported by a bearing on said base plate, a driving gear coacting with said gear on said screw, a hollow rectangular bottom lifting member 55 slidable in said upper rectangular portion of said standard to telescope therein and having a driving member secured in its lower end and having threaded engagement with said screw, a tubular top lifting member section telescopingly associated with said screw and said bottom lifting member section, and cables connected to said standard 60 and top lifting member section, and cables connected to said standard 65

and top lifting member section, said bottom lifting member section having rollers over which the cables are passed.

4. In a lifting jack, the combination of a hollow standard provided with a base plate, 70 a screw disposed vertically in said standard and provided with a gear at its lower end, said screw being supported by a bearing on said base plate, a driving gear coacting with said gear on said screw, a hollow bottom lifting member slidable in said standard to telescope therein and having a driving member secured in its lower end and having threaded engagement with said screw, a tubular top lifting member section telescopingly associated with said screw and said bottom lifting member section, and cables connected to said standard and top lifting member section, 75 said bottom lifting member section having rollers over which the cables are passed. 80

5. In a lifting jack, the combination of a hollow standard, a screw disposed vertically in said standard and provided with driving means at its lower end, a lifting member having threaded engagement with said screw and telescopingly associated with said standard, a second lifting member telescoping with said first named lifting member, and opposed cables connected at their inner ends to said second lifting member and at their outer ends to said standard, the first mentioned lifting member having rollers over which 90 said cables are passed. 95

6. In a lifting jack, the combination with a standard, of a lifting member telescoping 100 therein and comprising telescopingly associated sections, a screw with which the inner of said sections is telescopingly associated, the outer section having threaded engagement with said screw, and a cable connected to the 105 inner lifting member and to said standard, the outer lifting member being provided with a thrust member over which said cable is passed.

7. In a lifting jack, the combination with 110 a standard, a bottom lifting member section telescoping with said standard, a top lifting member telescopingly associated with said bottom lifting member, a vertically disposed screw with which said bottom lifting member has threaded engagement, means for driving said screw, a cable connected to the lower end of said top lifting member section and to said standard, and a member on said bottom lifting member section engaging said cable intermediate its connection to said top lifting member and standard. 115 120

8. In a lifting jack, the combination of a standard, a pair of lifting members mounted in telescoping relation to each other and to 125 said standard, a screw rotatably mounted in said standard and provided with driving means at its lower end, one of said lifting members having threaded engagement with said screw, and a cable connected to said 130

standard and to the other of said lifting members, the lifting member connected to said screw engaging said cable between its ends.

9. In a lifting jack, the combination of a standard, a pair of lifting members including a fast moving member and a slow moving member, a flexible connection between the fast moving member and the standard, a part on the slow moving member adapted to engage a bight of the flexible connection, said flexible connection being free to pass over said part, and means engaging the lower end of the slow moving member to raise the same to cause the part thereon to engage the bight of the flexible connection to raise the fast moving member.

10. In a lifting jack, the combination of a

standard, a pair of lifting members including a fast moving member and a slow moving member, a flexible connection between the fast moving member and the standard, a part on the slow moving member adapted to engage a bight of the flexible connections, said flexible connection being free to pass over said part and being connected to the lower end of the fast moving member, and means engaging the lower end of the slow moving member to raise the same to cause the part thereon to engage the bight of the flexible connection to raise the fast moving member. 30

In witness whereof I have hereunto set my hand.

ARTHUR C. HOPKINS.
